UNITED STATES PATENT OFFICE.

JOHN A. WIDNER, OF ALPENA, MICHIGAN.

HOSE-NOZZLE SUPPORT.

1,132,816.

Specification of Letters Patent. Patented Mar. 23, 1915.

Application filed May 11, 1914. Serial No. 837,889.

To all whom it may concern:

Be it known that I, JOHN A. WIDNER, a citizen of the United States, residing at Alpena, in the county of Alpena and State 5 of Michigan, have invented a new and useful Hose-Nozzle Support, of which the following is a specification.

The present invention appertains to a supporting or holding device for the nozzle 10 of a garden or lawn hose, and aims to provide a novel and improved contrivance of that nature.

The present invention contemplates the provision of a hose nozzle support or holder 15 of unique construction, which may readily accommodate the hose nozzle, and hold the same at a horizontal or vertical position, or at various inclined positions.

It is within the scope of the present invention to provide a device of the character 20 specified, which will be comparatively simple, non-encumbering, substantial and inexpensive in construction, as well as being convenient, practical and efficient in its use.

With the foregoing and other objects in view which will appear as the description proceeds, the invention resides in the combination and arrangement of parts and in the 25 details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:—

Figure 1 is a plan view of the improved hose nozzle support. Fig. 2 is a vertical 40 section thereof, taken on the line 2—2 of Fig. 1.

The present invention includes a base, which is in the form of a ring or annular metal casting 1, the same being provided at 45 diametrically opposed points, with upstanding lugs 2 and 3. The lugs 2 and 3 are provided with transverse apertures or openings 4 therethrough, said apertures being in alinement or coaxial.

The present support or holder embodies a 50 second element which comprises a bail-shaped or arch-like rod 5, which has its end or terminal portions bent angularly outward, as at 6 and 7, and journaled through

tively. The arch or bail 5 is resilient, in order that the angular ends or pintles 6 and 7 may be readily sprung into and out of engagement with the apertures 4 of the base member. The arch or bail 5 may thus be 60 swung about a line extending diametrically over the ring or annulus 1, and toward the respective opposite side portions of the ring 1, to bring the arch or bail 5 either at a horizontal, vertical, or inclined position. 65

The arch or bail 5 is held at any adjusted position, by means of a thumb or wing screw 8 threaded into the upper end of the lug 2 and adapted to bind or clamp against the end portion 7 of the arch or bail, the corresponding arm or limb of the arch or bail 5 being offset inwardly, as at 9, to accommodate the thumb piece of the set or clamping screw 8. If the lug 2 is offset or extended outwardly farther, the offset portion 9 of 75 the arch or bail 5 may be eliminated.

The arch or bail 5 is provided at its crest, with nozzle-receiving means, and to this end, the intermediate or central portion of the rod-like arch or bail 5 is hammered, 80 forged, or otherwise fashioned, to provide a transversely offset and curved portion 10 providing a socket or recess 10^a between the sections or limbs of the arch or bail 5, the adjacent ends of the bail or arch sections 85 projecting slightly beyond the ends of the clip portion 10, to provide retaining lugs 11 projecting slightly into the mouth of the opening or recess 10^a. The clip or keeper portion 10 is thus adapted to receive and 90 accommodate the ordinary nozzle of a garden or lawn hose, the nozzle being snapped laterally between the lugs 11 into the clip or keeper portion 10. When the nozzle is sprung between the lugs 11, the limbs or 95 sections of the arch or bail are adapted to yield, with the clip or keeper portion 10, to enable the nozzle to pass between the lugs 11 into the portion 10. The hose nozzle will then be embraced by the portion 10 and the lugs 11, the lugs 11 retaining the nozzle in 100 place, and it being noted that the portion 10 is relatively wide or broad, to prevent the nozzle from swinging. The nozzle may be readily withdrawn out of engagement with the arch or bail 5, by springing the nozzle outwardly from between the lugs 11, the sections or limbs of the bail or arch and the clip or keeper portion 10 connecting the adjacent ends of the said sections or limbs,

105

110

all being flexible or resilient to enable the nozzle to be readily applied to and removed from the holding means.

In practice, the base or ring 1 may be set 5 upon the ground, or other surface, and will hold the device in place, without the liability of the support or holder tilting. Then, when the nozzle of the hose is snapped into engagement with the clip or keeper portion 10 of the bail or arch 5, the nozzle may be held at a horizontal, vertical or inclined position by properly swinging or adjusting the bail or arch 5, as will be apparent. The stream or water discharged from the 15 nozzle may thus be directed in the manner desired.

When the device is not in use, the arch or bail 5 may be swung snugly against one side portion of the base or ring 1, in order 20 that the device may be compactly stored or conveyed.

Having thus described the invention, what is claimed as new is:—

1. In a device of the character described, 25 a base having upstanding lugs, an arch-like rod having its ends bent angularly and pivoted to said lugs, the arch having nozzle-holding means, and clamping means carried

by one of said lugs and coöperable with the respective end portion of said rod, to hold 30 the rod in various positions relative to the base.

2. In a device of the character described, an annular base having diametrically opposed upstanding lugs, the lugs having 35 transverse apertures, a bail-like rod having its end portions bent outward and journaled through the said apertures, the said rod having nozzle-holding means at its intermediate portion, and a set screw carried 40 by one lug and adapted to bind against the corresponding end portion of the said rod.

3. In a device of the character described, a base, a bail having its ends pivoted to the base and comprising sections and a clip 45 portion connecting the adjacent ends of the sections, the adjacent ends of the bail sections projecting beyond the ends of the said clip portion to provide retaining lugs.

In testimony that I claim the foregoing 50 as my own, I have hereto affixed my signature in the presence of two witnesses.

JOHN A. WIDNER.
